UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

CURTAIN-HANGER.

1,246,046.

Specification of Letters Patent. Patented Nov. 13, 1917.

Application filed July 5, 1917. Serial No. 178,567.

To all whom it may concern:

Be it known that I, JAMES H. BOYE, a citizen of the United States, residing at Chicago, in the county of Cook and State of Illinois, have invented certain new and useful Improvements in Curtain-Hangers, of which the following is a specification.

This invention relates to curtain hangers or supports, and has reference more particularly to that type of such devices which employ brackets attached to the window or door casings and rods or poles that are detachably mounted on and supported by said brackets.

15. The main object of my present invention is to provide an improved curtain hanger of the general type referred to which is adapted to support both a main curtain and a side drape or pair of side drapes, and in which it shall be possible to apply or remove either the main curtain or the side drape or drapes independently of and without disturbing the other. In some curtain hangers of this kind the inner ends of the short side drape rods are hooked over or otherwise supported on the main curtain rod. I have found that this is objectionable because tending to tear, rust and otherwise injure the hem of the main curtain in which the main curtain rod lies. Another object of my present invention, therefore, is to provide an improved construction wherein I obviate the above objection by supporting the inner ends of the side drape rods on independent brackets 35 that are so shaped and located as to be practically invisible from the front of the curtain and may, if necessary or desired, be swung on their attaching screws away from and toward the ends of the rods to facilitate the removal and application of the latter. Still another feature of the invention, which is not limited to a double hanger or a curtain and side drape hanger but may be used generally with the style of rod and 45 supporting bracket herein shown, resides in a new and improved separable joint between an end of the rod and the receiving socket of its supporting bracket which locks the rod in the bracket with sufficient force for 50 all service requirements and yet permits the two to be easily separated when it is necessary to take down the curtain.

My invention, its manner of use, and the

advantages inhering therein will be readily understood by those skilled in the art from the subjoined description taken in connection with the accompanying drawing which shows a practical and preferred embodiment of the invention, and wherein—

Figure 1 is a front elevation broken out between its ends of the curtain hanger;

Fig. 2 is a top plan view of Fig. 1;

Fig. 3 is an enlarged cross-section on the line 3—3 of Fig. 1;

Fig. 4 is a detail inner side elevation of one of the joints between the end of a rod and its supporting bracket;

Fig. 5 is a cross-section on the line 5—5 of Fig. 4.

Referring to the drawing, 10 may designate the upper cross-bar of a window casing to which my improved curtain hanger is applied. To this bar are secured as by screws 11 a pair of end brackets each comprising a pair of curved arms 12 and 13 that terminate at their free ends in rod-receiving sockets 12' and 13' respectively, the former lying directly in front of the latter. 14 and 15 designate the two telescoping sections of an extensible main curtain rod, the ends of which latter are removably engaged with and supported by the rear sockets 13' of the end brackets.

To the bar 10 are also attached, each preferably by a single screw 16 forming a pivotal or swinging connection, two intermediate brackets, each of which, as herein shown, comprises a forwardly and downwardly curved body portion 17 overhanging the main curtain rod and a horizontally curved 90 arm 18 at the lower end thereof that lies directly in front of the main curtain rod and terminates at its free end in a rod-receiving socket 18' that is in alignment with and faces the front socket 12' of one of the end brackets. 19 and 20 designate the two telescoping sections of an extensible side-drape rod, the ends of which latter are removably engaged with and supported by the front socket 12' of an end bracket and the aligned 95 socket 18' of an intermediate bracket.

Both the main and side-drape rods herein shown are of the substantially flat hollow type, but it should be understood that the specific form or type of rod employed is immaterial to the present invention in the

broad aspect of the latter. For the purposes, however, of this type of rod I have devised an improved joint for removably connecting the end of a rod to its supporting bracket, which is shown principally in the detail views, Figs. 4 and 5. By reference thereto it will be seen that the end of the rod carries a substantially semi-circular wire loop extension 21 that is secured in place 5 by mashing down the folded over portions of the sheet metal that together form the rear wall of the rod over the legs of the loop, as indicated at 22 in Figs. 3 and 4. The outer wall of the bracket socket which 10 receives this wire loop extension of the rod is indented to form on its inner surface a substantially circular convex lug or protuberance 23. The loop 21 is made of spring wire, and as the parts are forced together 15 under a relative endwise movement, the loop 21 bends sidewise and springs over and around the protuberance 23, thereby locking the end of the rod in the socket with sufficient force to prevent any accidental 20 displacement. A slight pull, however, suffices to separate them whenever it is necessary or desired to remove the curtain or side-drape from its supporting rod.

The side-drape rods are sometimes made 25 in a single piece. Such a rod may readily be removed by simply swinging the intermediate bracket on its fastening screw 16 away from the end of the rod and then withdrawing the other end of the latter from the 30 socket 12' of the end bracket, as indicated by dotted lines in Fig. 1.

It is believed that the subject-matter of 35 this invention and the manner in which it accomplishes the stated purposes and objects 40 thereof will be clearly understood without further description. Hence, without limiting the invention to the exact details shown and described,

I claim:

45 1. In a curtain hanger, the combination of a pair of end brackets adapted to be secured to a window casing, an intermediate bracket adapted to be secured to the window casing between said end brackets, a main curtain rod removably connected at its ends to and supported by said end brackets respectively, and a side-drape rod removably connected at its ends to and supported by 50 said intermediate bracket and one of said 55 end brackets.

2. In a curtain hanger, the combination of a pair of end brackets adapted to be secured to a window casing and each forming an end support for main and side-drape rods, a pair 60 of intermediate brackets adapted to be secured to the window casing between said end brackets and each forming an end support for a side-drape rod, a main curtain rod removably connected at its ends to and sup-

ported by said end brackets respectively, and 65 a pair of side-drape rods each removably connected at its ends to and supported by one of said intermediate and end brackets respectively.

3. In a curtain hanger, the combination of 70 a pair of end brackets adapted to be secured to a window casing and each formed with front and rear rod-receiving sockets, a pair of intermediate brackets adapted to be secured to the window casing between said end 75 brackets and each formed with a rod-receiving socket in alignment with the front socket of said end brackets, a main curtain rod engaged at its ends with and supported by the rear sockets of said end brackets, and side-drape rods engaged at their ends with and supported by the sockets of said intermediate 80 brackets and the front sockets of said end brackets.

4. In a curtain hanger, the combination of 85 a pair of end brackets adapted to be secured to a window casing and each forming an end support for main and side-drape rods, a main curtain rod removably connected at its ends to and supported by said 90 end brackets respectively, a pair of intermediate brackets adapted to be pivotally secured to the window casing between said end brackets, each of said intermediate brackets overhanging said main curtain rod 95 and at its free end providing an end support for a side-drape rod, and a pair of side-drape rods each removably connected at its ends to and supported by one of said intermediate and end brackets respectively. 100

5. In a curtain hanger, the combination of 105 a pair of end brackets adapted to be secured to a window casing and each formed with front and rear rod-receiving sockets, a main curtain rod engaged at its ends with and supported by the rear sockets of said end brackets, a pair of intermediate brackets adapted to be pivotally secured to the window casing between said end brackets, each of said intermediate brackets overhanging 110 said main curtain rod and at its free end formed with a rod-receiving socket in alignment with the front sockets of said end brackets, and side-drape rods engaged at their ends with and supported by the sockets of said intermediate brackets and the front 115 sockets of said end brackets.

6. In a curtain hanger, the combination with a substantially flat rod, of a spring wire loop secured to and projecting from an end 120 of said rod, and a supporting bracket having a flat receiving head or socket for said wire loop, a side wall of said socket being formed with an inturned protuberance over and around which said wire loop is sprung under 125 a relative endwise sliding movement of said loop and socket.

7. In a curtain hanger, the combination

with a substantially flat rod, of a spring wire loop of a substantially semi-circular form secured to and projecting from an end of said rod, and a supporting bracket having 5 a flat receiving head or socket for said wire loop, the outer side wall of said socket being indented to form a substantially circular internal protuberance having a convex surface over and around which said wire loop is sprung under a relative endwise sliding movement of said loop and socket.

JAMES H. BOYE.
